US0D1062620S

(12) **United States Design Patent** (10) **Patent No.:** **US D1,062,620 S**
(45) **Date of Patent:** **** Feb. 18, 2025**

(54) **WIRELESS CHARGER**

(71) Applicant: **Qianhai Junda (Shenzhen) Equity Investment Co., Ltd**, Shenzhen (CN)

(72) Inventor: **Zhuowen Liao**, Shenzhen (CN)

(73) Assignee: **Qianhai Junda (Shenzhen) Equity Investment Co., Ltd**, Shenzhen (CN)

(**) Term: **15 Years**

(21) Appl. No.: **29/877,699**

(22) Filed: **Jun. 9, 2023**

(30) **Foreign Application Priority Data**

Mar. 29, 2023 (CN) 202330161307.X

(57) **CLAIM**

The ornamental design for a wireless charger, as shown and described.

DESCRIPTION

FIG. 1 is a front, left and bottom perspective view of a wireless charger showing my new design;

FIG. 2 is a front, right and bottom perspective view of the wireless charger shown in a state of use;

FIG. 3 is a perspective view of the wireless charger shown in a folded state;

FIG. 4 is a perspective view of the wireless charger shown in a folded state and a state of use;

FIG. 5 is a front view of the wireless charger;

FIG. 6 is a rear view thereof;

FIG. 7 is a left side view thereof;

FIG. 8 is a right side view thereof;

FIG. 9 is a top plan view thereof; and,

FIG. 10 is a bottom plan view thereof.

The broken lines in the figures illustrate portions of the wireless charger that form no part of the claimed design.

1 Claim, 10 Drawing Sheets
